Primary Examiner — Vy Koenig*Assistant Examiner* — Kimberly Barnes(74) *Attorney, Agent, or Firm* — Hauptman Ham, LLP(57) **CLAIM**

I claim the ornamental design for a tile, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of the tile showing the new design;

FIG. 2 is a front view thereof;

FIG. 3 is a rear view thereof;

FIG. 4 is a left side view thereof, the right side view being a mirror image; and,

FIG. 5 is a top view thereof, the bottom view being a mirror image.

1 Claim, 5 Drawing Sheets
(2 of 5 Drawing Sheet(s) Filed in Color)(56)
